CLAIM

The ornamental design for a display device with graphical user interface showing a strategy baseline as shown and described.

DESCRIPTION

FIG. 1 is a front view of a first image of a display device with graphical user interface showing a strategy baseline according to the invention.

FIG. 2 is a second image thereof; and,

FIG. 3 is a third image thereof.

The appearance of the transitional image sequentially transitions between the images shown in FIGS. 1, 2, and 3. The process or period in which one image transitions to another image forms no part of the claimed design.

The stippling in the drawings shows contrast in appearance. The outermost even-dashed broken line showing an electronic device is for environmental purposes and forms no part of the claimed design. The smaller dashed broken line rectangle immediately adjacent to the outermost even-dashed broken line shows the display device and forms no part of the claimed design. The remaining broken lines show portions of the graphical user interface and form no part of the claimed design.

The dot-dashed broken line boxes illustrate the bounds of the claimed design and form no part thereof.
